UNITED STATES PATENT OFFICE

2,514,755

SWITCH BOX BRACKET

Norman C. Gardner, Granite City, Ill.

Application August 4, 1947, Serial No. 765,899

4 Claims. (Cl. 248—27)

1

This invention relates to a switch box bracket and it is an object of the invention to provide a device of this kind whereby a switch box may be securely held to a wall without the necessity of having screws or nails penetrating the wall.

It is also an object of the invention to provide a bracket whereby a switch box can be held to a wall without injury to the interior finish thereof, such as plaster or board.

The invention consists in the details of construction and in the combination and arrangement of the several parts of my improved switch box brackets, whereby certain advantages are attained, as will be hereinafter more fully set forth.

In order that my invention may be better understood, I will now proceed to describe the same with reference to the accompanying drawings, wherein:

Two forms of bracket are illustrated on the drawings; one for a round or octagonal outlet box and another for a square switch box.

In the drawings like reference numerals denote the same details in the different views.

Figure 1 is a face view of a ceiling bracket for a round or octagonal outlet box as seen from below the ceiling of a room and the outlet box in position, with some parts broken away.

Figure 2 is a vertical section on a plane taken along line 2—2 of Figure 1;

Figure 3 is a right hand face view of the bracket in Figure 2 only.

Figure 4 is a front elevation of a wall bracket for a square, double switch box, as viewed from the inside of a room, with some parts broken away;

Figure 5 is a face view of the main bracket member as seen from the inside of the wall;

Figure 6 is a vertical section on a plane taken along line 6—6 of Figure 4;

Figure 7 is a fragmentary radial section taken on a plane along line 7—7 of Figure 1.

In the embodiment of the invention as particularly illustrated in Figures 1 to 3 a ceiling board 10 or the like is provided with an opening 11 through which is inserted the switch box 12, herein disclosed as octagonal.

The bracket consists of two foundation members 13, 14 and two spider members 15, 16. The two foundation members 13 and 14 each have two straight, marginal straps 17 and 18 forming a right angle to each other and at the end of strap 17 an eye 19 is formed for engaging an adjusting rod 20, while the other strap 18 is provided with a series of similar eyes 21 all in alinement and adapted to have slidably disposed there-

2

through one of the wires or rods 20. By this means it is possible to make the foundation wider or narrower according to the size of hole 11, by sliding the rod or wire 20 of the members 13 and 14 through the eyes 21.

At right angles to each other and to the straps 17 and 18 of the members 13 and 14 are the tabs or narrow fingers 22 and 23, of which tab 22 is located at the outer extremity of strap 18, while tab 23 is located centrally of strap 17. A third tab or finger 24 runs diagonally inwardly from the junction between straps 17 and 18, while a fourth tab 25 likewise runs diagonally from the outer end of strap 17, where the single eye 19 is located. Both tabs or fingers 24 and 25 have pointed inner ends in order not to overlap the blunt ended tabs or fingers 22, 23, when the members 13, 14 are laid out flat for packing. The tab or finger 25 is provided with a longitudinal slot 26, the function of which will be explained later.

The two arms 15, 16 of the spider member are pivotally connected centrally as at 28, where they can be swung out at right angles to each other. These arms 15 and 16 are of a length to extend outwardly beyond the side wall of the box or receptacle 12 and the outer ends thereof are continued by the substantially perpendicularly related arms 29 of a length to extend outwardly through the opening 11 and folded thereover as at 30, said folded portions 30 being termed feet.

After this opening 11 has been cut thru the ceiling board 10 and the edges trimmed, the foundation members 13 and 14 are inserted through said opening and are joined together by the two rods or wires 20, and placed so that the inner edges of the straps 17 are properly spaced as determined by the size of the opening 11. Next the fingers 22 and 23 are folded out thru the opening 11 and bent outwardly over board 10, so that the latter becomes pinched between said straps 17, 18 and the fingers 22, 23, see Figure 2.

The next step is to insert the arms 29 of the spider arms 15 and 16, through the opening 10 and preferably with the arms 29 overlying and in close contact with the portions of the arms 22 and 23 within the opening. The arms 24 and 25 are also outwardly bended after which the box or receptacle 12 is applied with, of course its open face outwardly disposed. After the box or receptacle 12 has been properly placed within or through the opening 11, pull on the outer end portions of the arms 29 will bring the arms 15 and 16 closely adjacent to the inner or bottom wall of the box or receptacle 12 whereupon the portions of the

arms 29 outwardly beyond the wall 10 are outwardly folded, as at 30 to overlie the portions of the arms 22 and 23 lapping the wall 10.

The outer or extended portions of the arms 24 and 25 are then folded inwardly to tightly lap the wall of the box or receptacle 12. The slots 26 in the arms 25 are so positioned to allow the passage therethrough of the inwardly disposed and diametrically opposed lugs 31 carried by the outer or open end of the box or receptacle 12.

Lastly a flat collar 33 with a large circular opening 34 is placed around the opening 11 and overlying the spider feet 30. The collar is held tight by screws 34 threading through the box lugs 31, each of said screws extending through a recess *a* in the inner marginal portions of the collar.

In Figures 4, 5 and 6 is shown a wall bracket construction for a double switch box being a simplified construction of the invention and requiring no spider member for securing the box. In these figures reference numeral 40 represents a wall board with an opening 41 for the insertion of a switch box or receptacle 42, here represented as a double box with two switch buttons for which two windows 43 are here indicated in the guard plate 37 which completely covers the opening 41 on the inside of the room. It will be understood that the same construction can be used for single switch boxes, when the bracket will be adjusted to suit the width of the box.

As before, a foundation frame is provided, for placing over the opening 41 on the inner or rear surface of the wall board 40. This frame comprises two halves, 44, 45 which are a substantially duplicate. Each consists of a straight side strap 46 having three, straight, narrow fingers or tabs 47 directed inwardly from the side strap 46. Across one end of the latter two eyes 48 are shown for engagement with an adjusting rod 49 reaching across to second frame half.

At the opposite end of the side strap 46 an L-shaped side strap branch 50 is formed, which is provided with a series of eyes 51 intended for engagement with a second adjusting rod 49 having its opposite end portion held in the two eyes 48 of the second half of the foundation frame.

By advancing or separating the members 44 and 45 on the adjusting rods 49, a width suitable for the size of the opening 41 will be obtained. The L-shaped strap branch 50 has an inwardly directed finger 52 at right angles to the other fingers 47.

The switch box or receptacle 42 and the bracket frame are installed by first inserting the members 44 and 45 through the opening 10 to the rear of the wall. The two members are thereupon properly adjusted on the rods 49 as determined by the size of the opening 4.

The fingers 47 are then bent outwardly through the opening 41 and back upon the wall 40. The switch box or receptacle 42 is then inserted thru

the opening after the fingers 52 have first been bent upwardly. The fingers 52 are then bent back over the edge of the switch box or receptacle 42. This will hold the box in place for installation of the needed switch elements. Lastly the opening is closed by the shield or guard plate 37 and screws 54 drawn up tight in the threaded lugs 55 on the inside of the box 42.

All parts of the bracket are stamped or punched out of sheet metal, preferably galvanized iron.

It is to be understood that the invention as herein disclosed may be varied from the details described and shown without departure from the spirit of the subjoined claims.

I claim:

1. A bracket adapted to support a receptacle in an opening in a wall including two members, means for connecting said members for sliding movement one toward the other to adjust the bracket as determined by the size of the opening, bendable fingers carried by the two members to fold over the marginal portion of the opening to secure the same to the wall and additional bendable fingers carried by the two members for engagement with the receptacle to hold the receptacle to the bracket.

2. A bracket as set forth in claim 1, wherein the means for connecting the two members comprise a rod carried by each of the two members and disposed over the other, and means for slidably connecting each of the two members with the overlying portion of the rod of the other member.

3. A bracket as set forth in claim 1 further including a spider member to overlie the inserted end of the receptacle, said spider member comprising a plurality of arms of a length to extend beyond the receptacle, and additional arms carried by the extremities of the first arms and angular thereto, said second arms being of a length to extend through the wall opening and to overlie the marginal portion of the wall opening, said spider providing further means for holding the receptacle in position.

4. A bracket as set forth in claim 1, wherein the means for connecting the two members comprises two rods, one for each member, and mating eyes on the members through which the rods are directed to permit opposite sliding movements of the two members.

NORMAN C. GARDNER.
